(57)

CLAIM

The ornamental design for the golf ball extraction tool as shown and described.

DESCRIPTION

FIG. 1 is a perspective view of the golf ball extraction tool of the present invention; and

FIG. 2 is a front view of the present invention; and

FIG. 3 is a rear view of the present invention; and

FIG. 4 is a right side view of the present invention; and

FIG. 5 is a left side view of the present invention; and

FIG. 6 is a top view of the present invention; and,

FIG. 7 is a bottom view of the present invention.

The broken lines disclosed on the drawings form no part of the claimed design.

1 Claim, 5 Drawing Sheets
